UNITED STATES PATENT OFFICE.

CHARLES H. KRAUSGRILL, OF PORTLAND, OREGON.

MACHINE FOR MAKING CHECK-BOOK COVERS.

1,113,022.

Specification of Letters Patent.

Patented Oct. 6, 1914.

Application filed November 13, 1911. Serial No. 660,109.

To all whom it may concern:

Be it known that I, CHARLES H. KRAUSGRILL, a citizen of the United States, residing at Portland, in the county of Multnomah and State of Oregon, have invented certain new and useful Improvements in Machines for Making Check-Book Covers, of which the following is a specification.

At the present time, covers of check books, tablets, and the like, are made up of cardboard sides connected by gummed cloth. The cardboard stock used in making covers of this sort, is of light and heavy grades, according to the particular class of cover to be provided and frequently said covers are lined with paper, or the like, to provide a nicely finished article.

In the art of making covers for check books, etc., the gummed cloth or tape connecting the sides of the cover is applied by hand after the blank of material from which the cover is made is cut to provide said sides.

The purpose of the present invention has been to design a machine into which a blank of cardboard, or similar stock, may be fed, said blank being operated upon by suitable cutters so as to be separated to form the sides of a book cover, and mechanism being employed for applying gummed tape or cloth to the separated portions of the blank. The machine is also constructed to feed a lining to the cover sides or sections of the cut blank, which lining is adhesively applied in a manner which will be more fully pointed out hereinafter.

For a full understanding of the present invention reference is to be had to the following description and to the accompanying drawings, in which—

Figure 1 is a longitudinal sectional view of a machine embodying the invention, the section being taken on the line A—B of Fig. 2. Fig. 2 is a top plan view of the machine. Fig. 3 is a side elevation, certain parts being broken away. Fig. 4 is an end elevation of the machine. Fig. 5 is an enlarged detail view of the cutters. Fig. 6 is a sectional view of the same. Fig. 7 is a diagrammatic view showing the various feed rolls in their relative positions and indicating the direction of rotation of said rolls. Fig. 8 is a sectional view taken on the line C—D of Fig. 1. Fig. 9 is a top plan view of the glue tank or moistening means. Figs. 10 and 11 are additional views of said device. Fig. 12 is a plan view of a blank

cover in the condition in which it is produced by this machine. Fig. 13 is a sectional view of the cover shown in Fig. 12. Fig. 14 is a view similar to Fig. 12, showing a finishing covering paper, or similar material applied to the side portions of the cover. Fig. 15 is a plan view of a cover of very light material, as formed by the present machine, the action of the cutters being fully illustrated. Fig. 16 is a view similar to Fig. 5 showing the type of cutter without notches.

Throughout the following detail description and on the several figures of the drawings, similar parts are referred to by like reference characters.

The machine comprising the present invention embodies a plurality of feeding rolls which carry the blank of cardboard or equivalent stock from one end of the machine to the other. The blank as it enters the machine is fed forward by a suitable feed chain and operated upon by cutters which separate said blank into the sides of the book cover. As the cut blank progresses toward the delivery end of the machine, the separated portions of the blank have a moistened gummed tape adhesively applied thereto so as to connect the same, the feed rolls by which the blank is moved affording means for so applying the gummed tape and suitable shafts being supplied to carry rolls of finishing paper, cloth, or the like, which may be likewise applied to the cut sections of the blank, according to the desire of the operator and having in view the special use to which the cover may be put.

Referring to the drawings, 1 indicates a driving pulley carried by the shaft 2, and 3 is a bearing for said shaft.

4 denotes a driving gear meshing with an idler gear 5, and 6 and 11 are other gears that mesh with and drive gears 7 and 12.

Shaft 7^a supports the feed rolls 7^c and 7^d, 10 and 12^b and 12^c are cutters which are attached by keys, or the like, to shaft 12^a suitably supported by the frame of the machine and fixedly carrying gears 11 and 12. A sprocket chain 9 acts as a feeder for carrying the stock to the feed rolls 7^c and 7^d, said chain 9 passing around sprocket wheels 8 and 10. Pins on the chain 9 are adapted to directly engage the stock in the feeding operation. The train of gearing used on the machine also includes an idler gear 13 driven from the gear 11 and meshing with

the driving gear 14, the latter operating in conjunction with a gear 15 which operates the feed rolls 14^a and 15^a. An idler gear 16 is also driven by the gear 14 and meshes 5 with the gear 18. The shafts of the feed rolls 17^a and 18^a carry gears 18 which intermesh and one of which is in mesh with the gear 16 to derive motion therefrom.

19 is a roll driven by sprocket and chain. 10 connection 17^b which leads to the roll 17^a.

A gear 21 meshes with the gear 22, said gears being mounted on shafts of the rolls 21^a and 22^a respectively. The shafts upon which said gears are mounted are driven by 15 a sprocket and chain connection 20^c and gears 23 and 24 are in mesh and are driven by a sprocket and chain connection 22^c.

25 is a spool for holding gummed tape, said tape being adapted to unroll from the 20 spool 25 and passing over a moistening roll 26 mounted in the tank 26^a, from whence said tape passes upwardly between the rolls 14^a and 15^a, by which rolls the tape is applied by pressure to one side of the sections 25 of the blank which has been previously cut by means of the cutters 12^b and 12^c above mentioned. The arrangement of the gummed tape is shown clearly in Fig. 3. 27 is a second spool for gummed tape and similar spools are shown at 28, 30 and 32. Spool 30 32 is carried by shaft 32^a journaled in brackets 32^b upstanding from the frame of the machine.

The parts 28, 29 and 30 correspond respectively to the parts 25, 26 and 27 and may be used, if it is desired to apply more than a single strip of tape to the sections of the blank as cut or separated in the operation of the machine. The spool 26 is driven by 40 a belt 13^b leading from the pulley 13^a to the pulley 26^b on the shaft of the moistening roll 26^a. The roll 29 is adapted to be driven as shown in Fig. 3, by a pulley and belt connection 29^b leading from the opposite 45 end of the shaft of the roll 26^a.

31 denotes a moistening roll for use in moistening a tape running from the spool 32. 31^a is a water tank.

31^b and 31^c are shafts over which the tape 50 31^d passes and which support the tank 31^a, as shown in Figs. 5 and 6.

11^d—11^e is a clearer which operates in the curved portion of one of the cutters to maintain the same in unclogged condition.

55 7^b, 12^b, 18^b, 20^b, 22^b and 24^b are long screw bolts having suitable nuts operating thereon for regulating the pressure between the feed rolls.

31^g and 31^h are hooks adapted to support 60 the tank 31^a on the shafts 31^b and 31^c.

It will be apparent that when the blank of material is fed by the chain 9 to the feed rolls 7^c and 7^d, said blank will be carried onward to the cutters 12^b and 12^c, the latter 65 separating the blank into three pieces or

sections, the two outermost of which are adapted when cut into suitable sizes to form the cover of a book such as an ordinary check book, or the like. The two sides or portions of the blank above mentioned are 70 connected together by the gummed tape which is fed from the spool 25, or from one of the other spools hereinbefore described, according to the desire of the operator. The various feed rolls located at intervals 75 throughout the length of the machine carry the blank to the delivery end of the machine, and the center strip of material formed in the cutting of the blank, as described above, may be discarded or adhesively connected to 80 the gummed tape so as to form a reinforcement at the joint portion of the book to which the cover is applied.

As above premised, the sides of the book may be covered by a finishing paper or cloth, 85 in which event, said paper or cloth may be fed to the outermost cut portions of the blank from any one of the spools 25, 27, 28, 30 and 32.

As shown in Figs. 5 and 6, one of the 90 cutters has its cutting edge preferably notched and this style of cutter will be used particularly for the purpose of operating upon very light stock which cannot be handled well in this machine if cut into separated sections. By using the notched cutter, the stock will be cut so that the sections forming the cover of the book are held together by narrow webs instead of being entirely separated as would be the case with heavier stock. It will be understood, furthermore, that if the tape or cloth carried by the spool 27 or equivalent shafts, is not gummed, the moistening tanks referred to hereinbefore may contain liquid glue as an 105 adhesive to be applied to the tape as the latter is fed to the work.

In Fig. 16 I have illustrated cutters similar in construction and arrangement to those seen in Figs. 5 and 6, with the exception that the cutter disk shown as notched in Fig. 5 is illustrated in Fig. 16 as possessed of an uninterrupted periphery. The 110 said cutters consist of a disk 35 having a peripheral groove 36 into which extends 115 the periphery of the cutter disk 37.

In Figs. 13 and 14 are seen the cover blanks produced by a machine embodying the features of the present invention and utilizing cutters constructed as illustrated 120 in Fig. 16, which cutters are disposed to sever the blank into the cover portions 38, 38 and a back stiffening portion 39, the portions 38 and 39 in the continued operation of the machine being connected by the strip 125 40 gummed to the parts 38 and 39. This severing action is accompanied by the cutting of a strip of material from the blank for each set of cutters, the severed strip being of a width corresponding to the thick- 130

ness of the respective cutter, and thus the slots 53 are produced. It is to be noted that while the cutters sever the blank into the respective parts, the feeding apparatus 5 maintains the proper relation of the parts of the blank so that the gummed strip may be readily applied and the parts given their final relation without manual adjustment. When it is desired to have a more rigid 10 connection between the back portions, the blank is formed as indicated in Figs. 14 and 15 in which the back portion 39' is connected to the cover portions 38' by webs 41 of the material of the blank appearing 15 between adjacent ends of successive spaced slots 42 formed by the cutters, cutters of the type shown in Figs. 5 and 6 being employed for this purpose, and the notches 12^d affording web portions 41.

20 Having thus described the invention, what is claimed as new is:

1. In an apparatus of the class described, the combination of cutters, means for feeding a cover blank to the cutters, the cutters 25 being positioned for cutting slots in the blank leaving a stiffening back portion be-

tween the side portions of the blank and spaced therefrom, means for applying a strip connecting the side portions and the back portion, and means for guiding and 30 maintaining the relative position of said side portions and back portion during the application of the strip.

2. In mechanism of the class described, the combination with means for feeding a 35 blank, of cutters disposed to act upon the blank while being fed, the said cutters being notched for forming spaced slots dividing the blank into side portions and an intermediate back portion spaced from the side 40 portions and having webs connecting the back portion with the side portions, means for applying a strip connecting the side portions and the back portion, and means for guiding the blank during the applica- 45 tion of the strip.

In testimony whereof I affix my signature in presence of two witnesses.

CHARLES H. KRAUSGRILL.
